UNITED STATES PATENT OFFICE.

DANIEL L. THERIAULT, OF CORNWALL, ONTARIO, CANADA.

BUILDING CONSTRUCTION.

Application filed September 5, 1923, Serial No. 661,119. Renewed August 19, 1925.

To all whom it may concern:

Be it known that I, DANIEL L. THERIAULT, a resident of the town of Cornwall, in the Province of Ontario and Dominion of Canada, have invented certain new and useful Improvements in Building Constructions, of which the following is a specification.

This invention relates to improvements in building construction, and the objects of the invention are to provide an effective and economical construction of this kind that can be used without employing highly skilled labour, and in which the results obtained will be satisfactory in every way.

Further objects are to provide a construction of this kind that will be, to all intents and purposes, fireproof, and which can also be very rapidly completed.

With these and other objects in view, the invention consists in the combination and arrangement of parts described in the present specification and illustrated by the accompanying drawings that form part of the same.

Referring to the drawings, in which like characters of reference indicate corresponding parts in each figure, and in which:

Figure 1 is a front elevation, partly in section.

Figure 2 is a cross-sectional view.

Figure 3 is a section on the line 3—3, of Figure 1.

Figure 4 is a section on the line 4—4, of Figure 1.

Figure 5 is a section on the line 5—5, of Figure 4.

Figure 6 is a perspective detail of the strapping plate.

In the drawings:

The improved construction is shown as applied to an ordinary dwelling house, in which it comprises a foundation wall 10, preferably as illustrated of concrete, on which is secured a metal or steel wall plate

11. At each of the wall corners and at spaced intervals therebetween as may be required, there are embedded in the concrete foundation wall, stay bolts 12 formed with flat end portions 13 to retain them in the wall, and threaded at their other ends adapted to project through the wall plate 11.

15 are steel uprights or studs designed to be secured on the wall plate 11, by bolts 12 with securing nuts 16 and angle plates 17.

55 The studs 15 are preferably steel I beams

and have securely bolted thereon the wooden strips 18, to which are adapted to be secured on each side to form the structure walls, the plates 20 having bolt or spike orifices 21 therein.

When the plates 20 are secured, the wall structure between the studs or uprights 15 will be hollow, and up to the first floor may be filled, preferably, with sand in order to absorb all the moisture from the foundation 60 and the surrounding ground. For the second floor and above, the inside of the walls may have, instead of the steel plate 20, a covering of wall board or the like, which can be suitably finished to harmonize with 65 the interior, while the space between the inner covering of wall board and the outer covering of steel plates will form an air space.

For the flooring I beams are also used, 70 with the wooden strips bolted thereto, the only difference being that, instead of being laid sideways, they are laid flat, thus ensuring wooden securing means for the floors.

It will be readily seen from the foregoing 80 that a building constructed on these lines can be very quickly and economically erected. In putting up the outer covering of steel plates, provision can be easily made for the doors and windows, which are subsequently finished off in any well-known manner.

As many changes could be made in the above construction, and many apparently widely different embodiments of my invention within the scope of the claims, constructed without departing from the spirit or scope thereof, it is intended that all matter contained in the accompanying specification and drawings shall be interpreted 90 as illustrative and not in a limiting sense.

What I claim as my invention is:

1. Building construction of the character described, comprising, in combination, a foundation wall provided with a metal wall 100 plate having orifices therein, a plurality of stay bolts sunk in said walls and formed with threaded end portions projecting through the orifices in the wall plates, a plurality of I beams engaging with the stay 105 bolts and extending upwardly to form studs, wooden strips fixedly secured by means of bolts on said I beams, covering comprising a plurality of steel plates having orifices 110 therein and secured to said wooden strips

to form hollow walls, and moisture absorbing means for filling the hollow walls between the studs whereby moisture is absorbed.

- 5 2. In building structure of the character described comprising in combination with a foundation wall having a steel plate thereon and a plurality of stay bolts sunk in the wall and projecting through said wall plate, 10 a plurality of I beams having bolted thereto wooden strips and engaging with the stay bolts to form studs for the structure, steel plate covering secured to said wooden strips and extending therebetween on each 15 side to form hollow walls.

3. In building construction of the character described, the combination with a foundation wall having a steel plate thereon, of a plurality of steel uprights or studs fixedly secured to said plate and provided with 20 wooden strips bolted thereon, metal covering plates secured to said strips to form hollow walls between said studs, moisture absorbing means for filling the hollow walls for the first floor, said walls being left hollow 25 thereafter to form an air space.

In witness whereof I have hereunto set my hand.

DANIEL L. THERIAULT.
